UNITED STATES PATENT OFFICE.

LA ROY PACKARD, OF HAMMOND, INDIANA.

FOLDABLE CRATE.

1,175,804.

Specification of Letters Patent. Patented Mar. 14, 1916.

Application filed June 5, 1914. Serial No. 843,240.

To all whom it may concern:

Be it known that I, LA ROY PACKARD, a citizen of the United States, residing at Hammond, in the county of Lake and State 5 of Indiana, have invented new and useful Improvements in Foldable Crates, of which the following is a specification.

The invention relates to receptacles, and more particularly to the class of foldable 10 crates.

The primary object of the invention is the provision of a crate wherein the top, bottom, side and end walls can be folded into compact form when the crate is not in use, 15 so as to permit it to be stored in the least possible space or conveniently handled during transportation from one point to another.

Another object of the invention is the provision of a crate wherein the sections thereof are hinged together in a novel manner to permit the ready collapsing of the same or the setting up of the crate as the occasion requires.

A further object of the invention is the provision of a crate which is simple in construction, strong, durable, reliable and efficient in its purpose, and inexpensive in manufacture.

With these and other objects in view, the invention consists in the construction, combination and arrangement of parts as will be hereinafter fully described, illustrated in the accompanying drawings, and pointed 35 out in the claim hereunto appended.

In the drawings:—Figure 1 is a perspective view of a crate constructed in accordance with the invention. Fig. 2 is a vertical longitudinal sectional view thereof. Fig. 3 40 is a vertical transverse sectional view. Fig. 4 is a perspective view of the crate folded. Fig. 5 is a vertical longitudinal sectional view through the crate folded.

Similar reference characters indicate corresponding parts throughout the several views in the drawings.

Referring to the drawings in detail, the crate comprises a bottom 10, which in this instance is provided with a boarded floor 11, 50 although it may be of the open slatted form if desirable, sides 12, ends 13, and a top 14, the frames of which are fitted with rails 15 so that the same will be open for ventilating purposes.

At the outer face of the bottom 10 at one longitudinal edge thereof are metallic straps

16 formed with pintle eyes or sleeves 17 in which are loosely engaged the right angular pintle ends 18 of pintle posts or stems 19 engaged in clamp plates 20 secured to the outer face of one side 12, the opposite ends 21 of the stems or posts 19 being reversely bent at right angles thereto with respect to the pintle ends 18 and are engaged in staples 22 secured in the said side; thus the latter will 60 be swingingly connected to the bottom. On the outer face of the bottom 10 near the opposite longitudinal edge thereof are mounted pintle posts or stems 23, the same being of similar construction to the posts or stems 19 and having their pintle ends 24 engaged in sleeves or eyes 25 on metallic straps or leaves 26, the same being further provided with sleeves 27 in which engage the pintle ends 28 of the pintle posts or stems 29 which are fixed to the outer face of the other side 12, thereby swingingly connecting the same to the bottom 10. These sides 12 when folded outwardly and inwardly onto the outer face of the bottom 10 will lie one over 70 the other, the straps 26 being designed to permit this particular arrangement. Secured to the inner face of the bottom 10 at opposite ends thereof are metallic straps 30 provided with pintle sleeves or eyes 31 in 75 which engage the pintle ends 32 of pintle stems or posts 33 fixed to the inner faces of the ends 13, and this arrangement permits the latter to fold inwardly onto the inner face of the bottom 10 when the crate is collapsed. Secured to the inner face of the top 14 near one longitudinal edge thereof are pintle stems 34, the pintle ends 35 of 80 which engage in sleeves 36 on strap links 37, the same being further provided with sleeves 38 in which are received the pintle ends 39 of pintle stems or posts 40 which are secured to the outer face of one side 12 at the other longitudinal edge thereof, the top 14 being foldable outwardly and inwardly 85 onto the said side 12 to which it is connected when the crate is being collapsed, and this top is also free to be swung in the reverse direction for closing the crate when set up.

Pivoted to the inner faces of the sides 12 are hook catches 41 which are adapted to engage in eye members 42 secured in the ends 13 at the inner side thereof, and in this manner the sides and ends are fastened together when the crate is set up for use.

The top carries an ordinary hasp 43 which engages a keeper staple 44 carried by one

side 12 so that any ordinary well-known form of padlock or other locking means can be engaged with the keeper 44 for securing the top 14 closed.

5 It is to be understood of course that the pindle posts or stems employed are similar to the construction of the pindle posts or stems 19 hereinbefore set forth, and also the same are fastened in a like manner as the 10 said pindle posts 19 to the parts carrying the same.

From the foregoing it is thought that the construction of my invention will be clearly understood, and therefore a more extended 15 explanation has been omitted.

What is claimed is:—

A foldable crate comprising bottom, top, sides, and ends, strips fixed to one longer edge of the bottom and having pindle 20 sleeves, clamp plates secured to the outer face of one side, pindles mounted in the clamp plates and having reversely bent pindle ends, certain of said pindle ends being loosely engaged in the pindle sleeves, 25 staples engaging the remaining pindle ends and fastened in said side, pindle stems fixed

to the opposite longitudinal edge of the bottom and the other side respectively and having right angular pindle ends, links connecting certain of the said pindle ends for 30 swingingly uniting said side to the bottom and spacing it from the longitudinal edge adjacent thereto of the bottom, pindle stems fixed to the ends and having right angular terminals, sleeves on opposite ends of the 35 bottom and loosely receiving the last-named pindle ends, sleeves on one of said sides, pindle stems fixed in said sleeves and having right angle pindle terminals reversely disposed with respect to each other, pindle 40 sleeves on the top, pindle stems in said sleeves and having reversely extending right angular pindle terminals, and links connecting certain of the pindle terminals of the 45 stems on the top and side respectively.

In testimony whereof I affix my signature in presence of two witnesses.

LA ROY PACKARD.
